J. L. ROUSSEAU.
QUAD BLOCK OR MATRIX.
APPLICATION FILED JULY 24, 1915.

1,231,943.

Patented July 3, 1917.

UNITED STATES PATENT OFFICE

JOSEPH LEE ROUSSEAU, OF BROOKLYN, NEW YORK, ASSIGNOR TO MERGENTHALER LINOTYPE COMPANY, A CORPORATION OF NEW YORK.

QUAD-BLOCK OR MATRIX.

1,231,943.

Specification of Letters Patent.

Patented July 3, 1917.

Application filed July 24, 1915. Serial No. 41,637.

To all whom it may concern:

Be it known that I, JOSEPH LEE ROUSSEAU, a citizen of the United States, residing at Brooklyn, in the county of Kings and State of New York, have invented certain new and useful Improvements in Quad-Blocks or Matrices, of which the following is a specification, reference being had thereto in the accompanying drawing.

10 My invention relates to slug casting machines, such as linotype machines of the general organization represented in U. S. Letters Patent to O. Mergenthaler, No. 436,532, wherein a slug or linotype is cast 15 in a slotted mold against an assembled matrix line which produces the type characters thereon. Ordinarily the matrix line is composed of a series of individual matrices which circulate through the machine, but 20 in some instances it is made up of a single non-circulating matrix known in the art as a "quad block," and used particularly for the production of quads, rules, borders, and the like. As now constructed, the quad 25 block consists of a long body portion similar in cross section to an ordinary matrix and having in its front face a vertically disposed strip or plate containing in its side face the formative characters or matrix 30 proper.

In manufacturing the matrix strip, it is the practice to "rout out" its side face, or more generally speaking, to cut a long groove therein, and then punch or indent 35 the required matrix character in the bottom of the groove. This practice is expensive and besides is unsuitable for certain classes of work. Thus, it is often desired to cast slugs with type characters equal in 40 height to the thickness of the slugs, and this effect cannot be had from the ordinary matrix strip, since the height of the matrix characters therein is and must be less than the width of its groove or routing and 45 consequently less than the width of the mold slot. Other objections are also present,—for instance, difficulty is experienced in securing the proper alinement of the matrix characters with the mold slot, owing to the 50 clearance which must be allowed to permit the removal and insertion of the strip in the block. This difficulty becomes quite pronounced in the case of very thin slugs, such as for slender printing rules, which require 55 the use of a mold with an extremely small width of slot.

It is the aim of my present invention to overcome these and other objections and difficulties, and to this end, I propose to equip the quad block with a horizontally disposed matrix strip seated in a recess in the block with its operative or character-bearing edge located behind the front face thereof, and also with a filling piece arranged in the recess above the strip to hold it firmly down 60 upon its seat, the filling piece having its front face flush with that of the quad block, so as to leave in front of the matrix strip a longitudinal groove corresponding to the ordinary groove or routing of the block 65 but equal in width to the thickness of the strip. In this way, the preliminary routing of the strip is rendered unnecessary, and furthermore the height of the matrix characters thereon may be made equal to the 70 width of the routing or that of the mold slot, so that the slug will have its type characters of the same height as its thickness. This arrangement of the parts also considerably reduces the cost of manufacture, 75 and in some instances allows the matrix characters to be produced on the strip by machining instead of punching.

In the accompanying drawing I have shown my invention merely in preferred 80 form and by way of example, but obviously many changes and variations may be made therein which will still be comprised within its spirit. I desire it to be understood, therefore, that I do not limit myself to any 85 specific form or embodiment, except in so far as such limitations are specified in the claims.

Referring to the drawing:

Figure 1 is a perspective view of my improved quad block in assembled form and ready for use;

Fig. 2 is a similar view showing the matrix strip and filling piece detached from the block;

Fig. 3 is a section taken vertically through the quad block assembled;

Fig. 4 is a detail view; and

Fig. 5 is a sectional view of the quad block equipped with a different form of matrix strip.

Fig. 6 illustrates a modification.

My improved quad block consists as usual of a long body portion A similar in cross section to an ordinary matrix so as to be supported in a linotype machine in the regular way for co-operation with the mold. In

its front face, the body portion A is formed with a deep longitudinal recess A¹ whose lower wall A² is straight or flat and disposed horizontally or at right angles to the front face of the body portion, while its upper wall A³ is inwardly beveled or inclined. Located within the recess A¹ and seated flatly upon the horizontal wall A² is a thin matrix strip or plate B having its rear edge fitting tightly up against the rear wall of the recess and formed in its forward edge with a matrix character or characters B¹, which may be equal in height to the thickness of the strip. Also located in the recess A¹ is a filling piece C having its front face flush with that of the body portion A and provided on its bottom side with a longitudinal tongue C¹ engaging in a corresponding groove B² in the upper face of the matrix strip B, the opposite side of the piece being beveled so as to engage behind and be held in place by the beveled wall A³ of the recess. Screws D, threaded through apertures A⁴ in the body portion and bearing upon the upper edge of the filling piece, serve to clamp the latter firmly down upon the matrix strip and thus to insure the proper relationship of the several parts.

It will be noted that the width of the matrix strip B is slightly less than the depth of the recess A¹, so that its forward edge, containing the character B¹, stands behind the front face of the body portion A and thus provides a longitudinal groove E in front of the matrix character corresponding to the usual "routing." Since the height of the matrix character B¹ may be equal to the thickness of its strip B, it follows that it may also be equal to the full width of the groove E as well as that of the mold slot, so that the slugs produced from the quad block may be as thin as the strip B and with their type characters of full height, or extending entirely across their edges from one side to the other. Furthermore, the construction of the quad block is greatly simplified, requiring less accuracy in the manufacture of the parts, and in some cases allowing the formation of the matrix characters by machining instead of punching, as, for instance, when the matrix characters are straight cuts, or depressions designed for fancy borders, ornamental work, and the like. In such cases a number of matrix strips 55 may be arranged side by side and the matrix characters cut therein at one time.

When it is desired to produce slugs of other thicknesses or with type characters of different designs, the matrix strip B is removed, this being readily permitted by withdrawing the filling piece C endwise from the block after loosening the screws D. It will be understood, of course, that the substitution of a thicker matrix plate will also involve the use of a narrower filling piece.

Thus, in Fig. 5, the quad block is shown as equipped with a matrix plate F of considerably greater thickness than the plate B, requiring the use of a strip G of correspondingly reduced width. In other respects the parts are the same as those previously described, the piece G being formed with a longitudinal tongue G¹ fitting in a corresponding groove in the strip F, and the latter having its forward edge containing the character F¹ located in the rear of the front face of the quad block so as to leave in front of the character a groove or routing H, equal in width to the thickness of the strip.

Fig. 6 illustrates a further capability of my improved construction. Here the quad block is equipped with two matrix plates J and K located in the recess A¹, one upon the other and constituting in effect a single composite strip, a filling piece L of the necessary width being employed to hold them in place. By thus employing a plurality of strips, it is possible to produce slugs for printing, say wide, or compound border lines, etc. It will be apparent that by removing either one or both of the complementary plates and substituting others of another kind, a wide range of varied designs may be obtained.

As previously stated, I have shown my invention merely in preferred form and by way of example, and it will be obvious that many modifications and alterations therein will readily suggest themselves to those skilled in the art without departure from its scope. For instance, it might also be employed, if it were found desirable, in connection with the construction of the ordinary circulating matrices instead of a quad block, as illustrated in the drawing.

Having thus described my invention, its construction and mode of operation, what I claim and desire to secure by Letters Patent of the United States is as follows:

1. A matrix comprising a body portion formed in its front face with a longitudinal recess having its lower wall straight and horizontally disposed, a matrix strip located in the recess with its side face seated upon said wall and with its forward edge exposed, and a filling piece also located in the recess above the matrix strip with its front face flush with that of the body portion.

2. A matrix comprising a body portion formed in its front face with a longitudinal recess having its lower wall straight and horizontally disposed, a matrix strip located in the recess with its side face seated upon said wall and with its forward edge exposed, a filling piece also located in the recess above the matrix strip, and clamping screws for pressing said piece firmly down upon the matrix strip.

3. A matrix comprising a body portion

- formed in its front face with a longitudinal recess having its lower wall straight and horizontally disposed, a matrix strip located in the recess with its side face seated upon said wall and with its forward edge exposed, and a filling piece also located in the recess above the matrix strip with its front face flush with that of the body portion, said matrix strip and filling piece being interlocked with each other.
4. A matrix comprising a body portion formed in its front face with a longitudinal recess having its lower wall plain and horizontally disposed, a matrix strip located in the recess with its side face seated upon said wall and with its forward edge exposed, and a filling piece located in the recess above the matrix strip and having its front face flush with that of the body portion, and the said matrix strip having its forward or operative edge located behind the front face of the quad block so as to leave a longitudinal groove at the front thereof, for the purpose described.
5. A matrix comprising a body portion formed in its front face with a recess, a matrix strip located in the recess and having its forward or operative edge located behind the front face of the body portion, and a filling piece located in the recess with its front face flush with that of the body portion.
6. A matrix comprising a body portion formed in its front face with a recess, a matrix strip disposed horizontally in the recess and formed on its forward edge with a character equal in height to the thickness thereof, and a filling piece located in the recess and having its front face flush with that of the body portion.
7. A matrix comprising a body portion formed in its front face with a longitudinal recess having its lower wall straight and horizontally disposed, a matrix strip located in the recess with its side face seated upon said wall and with its forward edge exposed, and a filling piece also located in the recess above the matrix strip with its front face flush with that of the body portion, the said filling piece and strip being removable at will from the body portion to permit the substitution of other strips of different designs or thicknesses.
8. A matrix comprising the body portion formed with the longitudinal recess A¹ whose lower wall A² is straight and horizontal and whose upper wall A³ is beveled or inclined, the matrix strip B having its under face seated upon the lower wall A² and formed in its opposite face with the longitudinal groove B², and the filling piece C formed on its under side with its longitudinal rib C¹ engaging in the groove B² of the matrix strip and having its upper side beveled or inclined so as to engage 65 behind the beveled wall A³ of the recess A¹, all for the purpose described.
9. A matrix comprising a recessed body portion, a plurality of matrix elements located in the recess one above another, and a filling piece also located in the recess above the matrix elements with its front face flush with that of the body portion.
10. A matrix comprising a recessed body portion, a plurality of matrix elements located in the recess one above another, and a filling piece also located in the recess to one side of the matrix elements, said elements being removable at will and replaceable by others of different designs, for the purpose 80 described.
11. A quad block comprising an elongated integral body portion formed in its front face with a longitudinal recess having its lower wall straight and horizontally disposed, an integral matrix strip equal in length to that of the slug to be cast located in the recess with its side face seated upon said lower wall and with its forward edge exposed, and a filling piece also located in 85 the recess above the matrix strip with its front face flush with that of the body portion.
12. A quad block comprising an elongated integral body portion formed in its front 95 face with a longitudinal recess having its lower wall straight and horizontally disposed, and a relatively thin integral matrix strip equal in length to that of the slug to be cast and seated upon the horizontal wall of 100 said recess in a flatwise position so as to be disposed horizontally in the direction of its width, the said matrix strip having its forward or operative edge located behind the front face of the body portion.
13. A quad block comprising an elongated body portion formed in its front face with a longitudinal recess and a plurality of integral matrix strips equal in length to that of the slug to be cast seated in said recess one 110 above another, in the manner and for the purpose described.
14. A quad block comprising an elongated body portion formed in its front face with a longitudinal recess and a plurality of integral matrix strips equal in length to that of the slug to be cast seated in said recess one above another, said matrix strips being removable at will and replaceable by others of different design or thickness.
- In testimony whereof, I have affixed my signature in presence of two witnesses,
